UNITED STATES PATENT OFFICE.

CHARLES H. BOMBARDIE, OF SOUTH BEND, INDIANA, AND PAUL F. WEGNER, OF CHICAGO, ILLINOIS, ASSIGNORS TO WIREBOUNDS PATENTS COMPANY, OF KITTERY, MAINE, A CORPORATION OF MAINE.

BOX.

1,347,675.

Specification of Letters Patent. Patented July 27, 1920.

Application filed January 9, 1917. Serial No. 141,472.

To all whom it may concern:

Be it known that we, CHARLES H. BOMBARDIE and PAUL F. WEGNER, citizens of the United States, and residents of South Bend and Chicago, respectively, in the counties of St. Joseph and Cook, respectively, and States of Indiana and Illinois, respectively, have invented an Improvement in Boxes, of which the following description, in connection with the accompanying drawings, is a specification, like characters on the drawings representing like parts.

This invention relates to boxes and in its more specific aspect to that form of box known as a crate wherein the sides are made of spaced slats. The purpose of the invention is to provide a light and strong crate in which a minimum of expensive material is used. We also have in view the provision of a crate which may be used without a lid for measuring or storing purposes for vegetables, fruits or the like and to which a lid may conveniently be fastened by hand to provide a thoroughly substantial shipping container.

Our invention will be best understood by reference to the following description of one illustrative embodiment thereof taken in connection with the accompanying drawings, wherein:

Figure 1 is a perspective view of a crate with the top or lid separated from the body;

Fig. 2 is a view of the crate with the top secured in position;

Fig. 3 is a perspective view of the blank from which the sides and bottom of the crate body are formed;

Fig. 4 is a perspective view of one of the end sections; and

Fig. 5 is a view of one of the lower corners of the of the crate partly broken away.

Referring particularly to Fig. 3, a crate embodying one form of the invention may be made from a blank comprising three sections,—1, 3 and 5—all of which may comprise coöoperating cleats and side material; the side material preferably in the form of spaced slats 9, as shown, and the cleats 7 of the first and third sections, and cleats 8 of the middle section, preferably in the forms shown in Fig. 3, which sections are secured together in coöoperative foldable re-

lationship by longitudinal binding wires 11, secured by staples straddling same and driven through the side material into the 55 cleats and preferably by other binding wires 13 secured to the side material between the cleats. As will be well understood by those skilled in the art, the parts of the illustrative blank may be folded up into the position 60 they occupy in the completed box and the cleats will mate and the wires 11 and 13 may be tensioned across the dihedral angles of the box. In the embodiment of the invention illustrated, the cleats 7 on the side sections are provided with mortises; and the cleats 8 on the bottom section, when used, are provided with tenons adapted to enter the said mortises.

The end sections of the box are preferably 70 formed so that they may be locked into place in the process of folding up the box blank. For this purpose the illustrative end sections each include a cleat 15 corresponding to the top of the box and adapted to co-operate with the cleats 7 of the side sections and another cleat 17 adapted to interlock with the cleats of the sections which form the box body at a location remote from the cleat 15 to hold the end sections permanently 80 in place. The cleat 17 may also contribute to reinforce and stiffen the bottom section of the box. Wall-forming material is secured to the cleat 15 and the batten 17 and in the present instance spaced slats 19 are 85 utilized. Referring to Fig. 4, it will be noted that the lateral slats 19 are spaced from the shoulders of the cleats for a purpose hereinafter to be explained.

The cleat or batten 17 may be formed with 90 tenons like the cleat 15 and suitable mortises may be provided in the cleats 7 to receive the same. In the present embodiment of the invention the mortises 21 on the side cleats 7 are made of considerable depth so 95 that they are adapted to receive the tenons both on the cleats 8 and on the batten 17, as shown clearly in Fig. 5.

From the above description it will be apparent that the end sections can be 100 securely fastened when the side sections and bottom sections are folded into form by making the tenons on the cleat 15 and batten 17 enter the mortises on the cleats 7.

Any suitable means may be provided to hold the parts already described in form as an open-top box or crate. In the present embodiment of the invention we have shown 5 (see Figs. 1 and 2) suitable nails or dowels 23 passed through mortise and tenon at the upper corners of the box.

To close the box a preferably detachable cover is provided which may be made of 10 the same material as is used for the sides of the box body. In the present instance it is composed of a number of slats 25 connected by binding wires 27 and 29 corresponding in position respectively to the 15 wires 11 and 13 of the box body. The cover may be placed on top of the box after it is filled and the wires of the cover engaged with those of the box body and a box having continuous wire bindings and possessing 20 practically unimpaired the advantages of the so-called "wirebound" box is the result. Referring to Fig. 2 it will be noted that the ends of the box are surrounded by continuous wire bindings and these bindings 25 are, except on the cover side, secured through the side material and to the cleats, where they will, as is well known, offer the greatest resistance to breakage of the box.

While the wire bindings may be made 30 continuous in any desired way, preferably readily detachable fastening means are provided so that the parts can be readily assembled by hand and so that the box may be opened and re-used a number of times.

35 For this purpose we may conveniently provide a box with the prepared fasteners, which are formed by bending back the wire on itself and intertwisting the ends with the standing parts. Through the loop thus 40 formed in one wire, the twisted body of a coöperating wire may be inserted and bent over into a hook, as clearly shown in Fig. 2, the throat of this hook being preferably formed of a double thickness of twisted 45 wire. This fastening may be readily made and released a number of times without impairing the strength of the wire and when the box is used as an open-top container no raw ends of wire are left projecting to 50 tear the clothes or hands.

It will be noted that by spacing the lateral slats 19 of the end sections from the shoulders of the tenons that spaces 31 are provided adjacent the sides which assist in 55 the thorough ventilation desired in a crate and also result in an economy of material. As the cleats 15 and 17 reinforce the crate walls, less and thinner wall material is required.

60 It will be apparent from the above description that we provide a box or crate in which very thin material may be used because the strength of wire is depended on rather than the strength of wood for with- 65 standing the strains of shipment. Our em-

bodiment also provides a form of crate which may be readily used without the top as a storage or shipping receptacle, but which is provided with a top which can be easily stored away and attached to the crate 70 for shipping purposes whenever desired by the grower or farmer. When the crate is used without the top, it will be noted that the cleat 15 not only securely holds the parts in form and prevents them from wabbling 75 or collapsing but that it also provides a handle whereby the crate may be lifted. The construction of our crate and the novel manner of attaching the end thereto reduces to a large extent the number of nails or 80 separable fasteners ordinarily used in assembling a box or crate and a greater ease and rapidity of assembling than is afforded by the methods now in use is provided for. At the same time the parts may conveniently 85 be shipped in knock-down, as shown in Figs. 3 and 4 and easily assembled without the use of special machinery or skilled labor. The lid may be conveniently fastened on without the use of nails or other separate 90 fastening means and by the provision of the integral hook-and-eye fastenings it is practicable to open and close the crate and fasten it for shipment a number of times without impairing the strength either of the 95 crate or of the fastening means. On the other hand, if desired, the top section may be nailed to the cleat 15 and the bottom section may be nailed to the cleat 17.

We have described in detail the typical 100 example of our invention disclosed in the accompanying drawing, but all the structural features shown and referred to are not, of course, essential to our invention in its broader aspect. We do claim as our invention:—

1. A wirebound box comprising separate sections of side material and cleats for the sides and bottom of the box connected together in foldable relationship by binding 110 wires secured to cleats of said sections; and separable end sections having transverse cleats secured thereto detachably engaging said cleats of the side sections in a manner to prevent inward or outward displacement 115 of said end sections and hold the parts in box form independently of a lid.

2. A wirebound box comprising relatively foldable side and bottom sections having coöperating end cleats and connected by 120 binding wires secured to said cleats; separable cleats for the fourth side of the box holding said parts in box form independently of a lid; a separate lid comprising side material directly applied to said cleats 125 for the fourth side; and separate wires connecting said binding wires across the fourth side and securing said lid.

3. A wirebound box comprising relatively foldable side and bottom sections connected 130

by binding wires; cleats on said side sections to which said binding wires are secured; separable end sections having cleats for the fourth side of the box having mortise and tenon connections with the cleats of the side sections; a separate lid resting on said cleats for the fourth side; and separate wires connecting said binding wires across the top of the box and securing the lid.

4. A box comprising, in combination, four side sections and one or more end members, two oppositely disposed side sections having cleats secured thereto and forming parts thereof, an end member having a cleat secured thereto and forming part thereof and engaging at its ends with the adjacent side section cleats to assist in holding said cleated side sections and the end in box form, said end member cleat being located substantially flush with ends of the engaged side section cleats to define therewith an end cleat frame, a third uncleated side section intervening between said oppositely disposed cleated sections and resting upon said end member cleat, and wire binding encircling the box in the plane of said end cleat frame and secured to the cleats of said cleated side sections and passing over and secured to said uncleated section, thereby holding said uncleated section against said end member cleat and maintaining said end member cleat in its engagement with said side section cleats.

5. A box comprising three relatively foldable side sections connected by binding members, the intermediate section having a tenoned reinforcing cleat at each end and the lateral sections having mortised reinforcing cleats adapted to coöperate therewith, end sections having transverse tenoned reinforcing members arranged to enter the mortises of the cleats of the side sections to hold the ends in position.

6. A crate having three relatively foldable side sections connected by binding wires, each section comprising spaced slats and end cleats coöperating with the end cleats of adjoining sections; end sections each comprising a cleat for the fourth side of the box coöperating with the cleats of opposite side sections and another cleat remote from the first having provision for interlocking with the said cleats of opposite side sections, and slats secured to said cleats of the end sections; the coöperation of the said cleat for the fourth side and the interlocking of the other cleat of the end sections with the said cleats of the opposite side sections serving to retain the end sections against inward or outward displacement; and means retaining the said opposite side sections in place against the end sections.

7. A crate having three relatively foldable side sections connected by binding

wires, each section comprising spaced slats and end cleats coöperating with the end cleats of adjoining sections; end sections each comprising a cleat for the fourth side of the box coöperating with the cleats of opposite side sections and another cleat remote from the first having provision for interlocking with the said cleats of opposite side sections, and slats secured to said cleats of the end sections; the coöperation of the said cleat for the fourth side and the interlocking of the other cleat of the end sections with the said cleats of the opposite side sections serving to retain the end sections against inward or outward displacement; and means retaining the said opposite side sections in place against the end sections, and a separate lid comprising spaced slats adapted to be applied to said cleat for the fourth side and having binding wires corresponding to binding wires on the cleat body and adapted to be connected therewith.

8. An open top box comprising three side sections, two thereof comprising side material and reinforcing end cleats and being oppositely disposed in the box, binding wires attached to said side material and to the third side section, end sections comprising side material and upper and lower cleats, the upper cleats of the end sections being engaged with the cleats of the two oppositely disposed side sections in a manner to prevent displacement thereof inwardly or outwardly of the box, whereby a rigid open top box of knock down construction is provided.

9. A box comprising in combination; three side sections, two thereof comprising side material and reinforcing end cleats and being oppositely disposed in the box, binding wires attached to said side material and to the third side section, end sections comprising side material and upper and lower cleats, the upper cleats of the end sections being engaged with the cleats of the two oppositely disposed side sections in a manner to prevent displacement thereof inwardly or outwardly of the box, and a cover section comprising side material and binding wires adapted to fit directly upon said upper cleats of the end sections with the binding wires thereon in alinement with the binding wires of the three side sections.

10. A wirebound open-top box comprising three separate sections of side material and cleats corresponding to the sides and bottom of a box secured together in foldable relationship by continuous binding wires, and ends for the box having transverse cleats secured thereto and adapted to form a mortise and tenon engagement with the cleats of the side sections of the box to hold the ends against inward or outward displacement.

11. A wirebound open top box comprising

three separate sections of side material and cleats corresponding to the sides and bottom of a box, secured together in foldable relationship by continuous binding wires ¹⁰ 5 cured to cleats of said sections; and separable ends for the box having transverse cleats secured thereto and adapted to de-

tachably engage the cleats of the side sections in a manner to hold the ends against inward or outward displacement.

In testimony whereof we have signed our names to this specification.

CHARLES H. BOMBARDIE.
PAUL F. WEGNER.
